UNITED STATES PATENT OFFICE.

JOSEPH K. W. CARSON, OF WINCHESTER, KANSAS.

DESIGN FOR A FERRULE.

SPECIFICATION forming part of Design No. 35,420, dated December 10, 1901.

Application filed October 31, 1901. Serial No. 80,701. Term of patent 14 years.

● *To all whom it may concern:*

Be it known that I, JOSEPH K. W. CARSON, a citizen of the United States, residing at Winchester, in the county of Jefferson and State of Kansas, have invented and produced a certain new and original Design for Ferrules; and I do declare the following to be a full, clear, and exact description of the invention, such as will enable others skilled in the art to which it applies to make and use the same.

The invention relates to a new and original design for a ferrule designed to be secured to the end of a vehicle tongue or pole; and it consists of a design of the configuration shown in the accompanying drawings, in which—

Figure 1 is a side elevation, and Fig. 2 is a longitudinal vertical sectional view.

The leading feature of the design comprises a tapering tubular portion 1, having a closed beveled end 2, with rounded corners 3, and an oval flange 4, projecting downwardly from the under side of the tubular portion and provided with an opening 5.

What I claim is—

The design for a ferrule, as herein shown and described.

In testimony whereof I have hereunto set my hand in presence of two subscribing witnesses.

JOSEPH K. W. CARSON.
